UNITED STATES PATENT OFFICE.

RALPH P. BUCKLAND, JR., AND GUSTAVUS A. GESSNER, OF FREMONT, OHIO.

IMPROVEMENT IN PHARMACEUTICAL STILLS, STEAM, AND WATER-BATHS.

Specification forming part of Letters Patent No. 117,738, dated August 8, 1871.

To all whom it may concern:

Be it known that we, RALPH P. BUCKLAND, Jr., and GUSTAVUS A. GESSNER, of Fremont, Sandusky county, Ohio, have invented a Pharmaceutical Still; and we do hereby declare the following, when taken in connection with the accompanying drawing and the letters of reference marked thereon, to be a full, clear, and exact description of the same.

The object of this invention is to make a simple, cheap, and efficient pharmaceutical still for the economical preparation of fluid and solid extracts, essences, distilled and medicated waters, sirups, &c.

In the drawing, Figure 1—A represents a support for the bath; B, a stove, (any kind of stove or gas-furnace may be used with this apparatus;) C, the water-bath, which may be converted into a steam-bath, if desired, by keeping just enough water in the apparatus to fill the pipe c^2 ; F, the condenser surrounding the top of the retort, kept full of cold water by a supply-cock, (not shown,) has attached to its upper edge a small pipe, f , which carries off the waste water; I, the heater, to be placed on a stove or gas-furnace and connected, by a pipe, i^1 , with a circular pipe, i^2 , inside of and near the top of the vessel C, and, by pipe c^2 , with the bottom of vessel C. J is a small vessel, connected, by a pipe, j^1 , with pipe c^2 , and is supplied with a waste-pipe, j^2 , Fig. 2, on a level with the top of the water-bath. This vessel receives the water from the waste-pipe f , whereby the water in the vessel C is always kept up to the proper level and the dissipation of the bath is prevented. Fig. 2— c^2 , a small groove around the inside of the top of vessel C; D, a retort suspended within the vessel C by a ring, d^2 , which rests in the groove c^1 . This joint can be made steam and water-tight by filling the groove with putty or other cement before setting the ring d^2 into it. E, the cover of the retort, consisting of an upright circular band, e^1 , which, resting on the flaring ring d^1 , forms a groove, $d^1 e^1$, which is to be filled with cement, thus forming an air-tight joint and a corrugated cone, E, the base of which, with the beveled upper edge of the upright circular band e^1 , forming a gutter, e^2 , which opens into the pipe g , Fig. 3, for carrying off the condensed liquids. i^2 , a circular pipe, connected by pipe i^1 with the top of the heater I, and having from four to eight or more openings into the vessel C. By this ar-

rangement a perfect current of hot water or steam is obtained from heater I through pipes i^1 i^2 and vessel C and back again by pipe c^2 to the heater. As the hot water or steam enters the bath near the top and at from four to eight or more different points simultaneously, the sides and bottom of the retort containing the substances to be acted upon can be evenly and rapidly heated. Fig. 3—G, a small condenser, commonly called a Liebig's condenser, surrounding pipe g to prevent the escape of any uncondensed vapor; H, a funnel, placed under the supply-cock (not shown) and connected by pipes h^1 and h^2 with the condensers F and G; pipe h^1 carries a stream of cold water to the bottom of vessel F and upon the commencement of pipe g ; h^2 supplies condenser G with a constant stream of cold water. Fig. 4—K, a support for the condenser G, represents a transverse section of the vessel C, showing pipes i^1 i^2 c^2 and heater I and the manner in which the hot water or steam is made to circulate through the pipes, heater, and bath.

The method of operating this still is as follows: The top, including parts E, F, and G, and the retort D being removed, the groove c^1 is filled with putty or other cement. The retort is now replaced, and the ring d^2 is firmly pressed into the cement. The substances to be treated are introduced into the retort and the top (E, F, and G) replaced, and the groove $d^1 e^1$ filled with some cement. The water is now turned on and a fire made under the heater. As the water in the heater becomes hot it will rise into pipes i^1 and i^2 , and through the openings in pipe i^2 into vessel C. Cold water from pipe c^2 and lower part of vessel C will flow into the heater, and, after being heated, will be forced up through the pipes into the bath. Thus in a short time a current is established which will continue as long as heat is applied. As the current of hot water is in contact with the sides and bottom of the retort, the volatile constituents of the substances treated are converted into vapor, which, rising until it comes in contact with the cold under surface of the cone E, is condensed and runs down into the gutter e^2 , and from thence into the pipe g , from which it may be conducted into any kind of vessel.

For a steam-bath the operation is the same as above except that the lower pipe only is kept filled with water.

This still can be used in connection with any

kind of stove or gas-furnace; is simple, cheap, efficient, and durable; combines a steam and water-bath in one apparatus, and operates with rapidity and thoroughness.

We claim as new—

1. The combination of the heater, the steam or water-bath, and the still, with their connecting pipes, substantially as set forth.

2. The circular pipe i^2 , whereby the hot water or steam is made to enter the bath at from four to eight or more different points simultaneously.

3. The joints d^1, e^1 and d^2, e^1 .

4. The arrangement of pipes f, j^1 , and j^2 , with the vessel J , substantially as set forth.

5. The corrugated cap with surrounding vessel, in combination with the small condenser.

RALPH P. BUCKLAND, JR.
GUSTAVUS A. GEESNER.
